UNITED STATES PATENT OFFICE.

TIMOTHY E. SHEA, OF RUTHERFORD, NEW JERSEY, ASSIGNOR TO WESTERN ELECTRIC COMPANY, INCORPORATED, OF NEW YORK, N. Y., A CORPORATION OF NEW YORK.

ELECTRICAL CIRCUITS.

Application filed February 27, 1926. Serial No. 91,220.

This invention relates to electrical circuits and particularly circuits consisting of resistance networks in combination with equalizers or other networks, and has for an object to improve the design of such circuits; particularly to increase the latitude of choice of impedance elements which may be used in a network designed to have a given transmission characteristic.

10 Networks consisting solely of resistance elements arranged in T or Π form, are often employed to produce a desired attenuation, as, for example, to prevent overloading in repeaters. Such networks are commonly referred to as pads. In circuits employing a pad it is the practice to design the pad so that its impedances match the impedances of the circuits to which it is connected. Heretofore, so far as known, when an equalizer network was used in such a combination it was connected to one set of terminals of the pad and given the same impedance as the pad and circuit to which it was connected. With such an arrangement, the 20 values for the elements of the equalizer are fixed by the transmission characteristic desired and the impedance of the pad with which it is associated. Often, impedance elements of values thus determined cannot be economically obtained.

In accordance with this invention the resistance pad is split and the network inserted within it, thus giving it a new value of impedance, equal to the impedance of the pad at the split point. This method gives a considerable latitude of choice of elements for the network since the pad can be split at a point which gives a desirable impedance.

40 This invention can be more readily understood by reference to the following detailed description in connection with the drawing in which: Fig. 1 shows a generalized circuit of a network and T type pad connected in series; Fig. 2 a specific example of the circuit of Fig. 1; Fig. 3 a generalized circuit of a network inserted within a T type pad in accordance with this invention; Fig. 4 a

specific example of the circuit of Fig. 3; Fig. 5 a generalized circuit of a network connected in series with a Π type pad; Fig. 6 a specific example of the circuit of Fig. 5; Fig. 7 a generalized circuit of a network inserted within a Π type pad in accordance with this invention; Fig. 8 a specific example of the circuit of Fig. 7; Fig. 9 a generalized circuit of another method of inserting a network within a T type pad; and Fig. 10 a generalized circuit of another method of inserting a network within a Π type pad.

Fig. 1 shows a T type pad comprising the series resistances R_a and R_b and the shunt resistance R_c connected between terminals 11, 12, 13 and 14. At the terminals 13 and 14, the pad is adapted to be connected to a circuit having an impedance Z_1 while at the terminals 11 and 12 it is adapted to be connected to an impedance Z_2 . The pad is therefore designed so that the impedance looking into it at the terminals 13 and 14 is Z_1 and at the terminals 11 and 12 is Z_2 . Connected in tandem with the pad is a generalized attenuation correcting network of the constant resistance type described and claimed in U. S. Patent 1,603,305, issued October 19, 1926, to O. J. Zobel. This network comprises the resistance R and the generalized impedance Z_{11} connected in parallel with one another in the series arm and a generalized impedance Z_{21} connected in the shunt arm. The impedance elements of this network are designed to have values which give the network a required transmission characteristic and an impedance equal to Z_2 .

85 In Fig. 2 is shown a specific example of the circuit of Fig. 1. Here it is assumed that the impedances between which the pad 16 is required to work are $Z_1=700\omega$ and $Z_2=1200\omega$ which are representative values. 90 The arms of the pad are then given the values indicated, namely $R_a=897\omega$, $R_b=344\omega$, and $R_c=430\omega$ in order to provide sufficient attenuation for the purpose required and to match the impedances of the connected circuits. 95 A transmission characteristic is as-

sumed which requires that the impedance Z_{11} of the network 16 be an inductance and capacity in series and impedance Z_{21} an inductance and capacity in parallel, both 5 resonant at 24,100 cycles per second with this assumption, in order to give the network 16 an impedance equal to Z_2 (1200ω), the elements would have to be given the values indicated. It would be very uneconomical 10 to construct a coil having an inductance of .180 h. which is the value required for the series coil since it would be difficult to make the distributed capacity of such a coil of a value which would not be of the same order 15 of magnitude as that of the series condenser which has a capacity of only .000242 mf. This difficulty is overcome by the circuit of this invention illustrated in Figs. 3 and 4.

Fig. 3 shows a pad and a network arranged 20 to be connected between two impedances Z_1 and Z_2 as in Fig. 1. In this case, however, the pad is split into two portions 13, 14, 17, 18, and 19, 20, 21, 22 so that the network 16 may be inserted therebetween to give it a 25 more desirable value of impedance. In the embodiment shown in this figure, the pad is broken by splitting the resistance R_a into two portions R_a' and $R_a - R_a'$. The impedance Z_3 of the pad is then $Z_2 - R_a'$. Referring to Fig. 4 it will be seen that in a circuit 30 designed to meet the requirements of Fig. 2 the impedance of the network is reduced to 600 ohms, by splitting the pad in this way and the values for the impedance elements 35 are changed to those indicated, which may be more economically obtained in practice.

Fig. 9 shows a generalized circuit illustrating the method of inserting the network in a T type pad by splitting the shunt resistance R_e , which may be desirable in some cases in 40 order to obtain an optimum value for the network impedance.

Fig. 5 shows a circuit similar to that of Fig. 1 except that in this case the pad is of 45 the II type composed of a series resistance R_b and two shunt resistances R_a and R_e .

Fig. 6 shows a specific example of this type of circuit in which the impedances between which it is connected are $Z_1 = 700\omega$ and 50 $Z_2 = 1200\omega$ as was assumed for the circuit of Fig. 2. Assuming in this case a transmission characteristic such that the network 16 must consist of series and shunt arms resonate at 210 cycles per second, it would then be necessary to give the elements the values indicated. Condensers of capacity .24 mf. and 1.65 mf., respectively are thus obtained. Since the cost of condensers of capacity greater than 55 0.1 mf. varies practically directly with their size a more economical design of the network can be obtained by reducing these capacities. This can be done by the arrangement of this invention shown in Figs. 7 and 8 in which the pad is split into two portions 33, 34, 35, 36

and 37, 38, 39, 40. This is accomplished by 65 splitting the shunt resistance R_a into two portions, R_a' and R_b . With this arrangement the values for the elements are as follows:

$$R_a = \frac{Z_2 Z_3}{Z_3 - Z_2} \text{ where } Z_3 > Z_2$$

$$\text{and } R_a' = \frac{Z_3 R_a}{R_a - Z_3}, \text{ where}$$

$$R_s = R_b + \frac{R_e Z_1}{R_e + Z_1} \text{ and } R_s > Z_3$$

Fig. 8 shows a specific example of this 80 type of circuit designed to meet the requirements assumed for the circuits of Fig. 6. The pad is split to insert the network at a point at which the impedance Z_3 is 1800 ω . With this arrangement values of .16 mf. for 85 the series condenser and 1.1 mf. for the shunt condenser are obtained. This gives a total capacity of 1.26 mf. as compared with 1.89 mf. for the network of Fig. 6, which results in a considerable saving.

Fig. 10 shows a modification of the circuit of Fig. 7 in which a II type pad is split by dividing the series resistance R_a . This arrangement may be desirable in some cases in order to obtain an optimum value for the 95 impedance of the network.

What is claimed is:

1. In an electrical circuit having two portions, a pair of four-terminal resistance networks included between said portions and connected respectively thereto at a pair of terminals, said networks being proportioned to present to the circuit portions to which they are respectively connected, impedances equal to the circuit impedances, and to have 100 impedances at their other pairs of terminals equal to each other and different from the impedances of either of said portions and having an attenuation equivalent to that of a single resistance network of series and 105 shunt resistance elements so proportioned that it would match the impedances of said portions if connected alone therebetween, and a network comprising reactive impedance elements connected between said resistance networks, said reactive impedance network having an impedance equal to the impedance of said resistance networks at the 110 terminals to which it is connected.

2. A combination according to the preceding claim in which said impedance network is a constant resistance attenuation correcting network.

3. A method of combining a network of impedance elements designed to give a desired transmission characteristic and to match the impedance of the circuit to which the network is connected, with a resistance net-

work of series and shunt resistance elements, so as to obtain economical values for the impedance elements of the network which comprises dividing the resistance network into two portions at a point which will give a desired impedance different from the impedance of the resistance network at either

terminal, and connecting the network of impedance elements within the resistance network at that point.

10

In witness whereof, I hereunto subscribe my name this 26th day of February A. D., 1926.

TIMOTHY E. SHEA.
